United States Patent

Des. 242,508
Patented Nov. 30, 1976

242,508

SEAT

Robert A. Skyer, Palatine, and George E. Bowman,
Country Club Hills, Ill., assignors to International
Harvester Company, Chicago, Ill.

Filed Sept. 5, 1975, Ser. No. 610,703

Term of patent 14 years

Int. Cl. D6—01

U.S. Cl. D6—47

FIG. 2

FIG. 4-FIG. 3-FIG. 5-FIG. 1 is a perspective view as seen from the right front of a seat embodying our new design;

FIG. 2 is a plan view thereof;

FIG. 3 is a side view thereof;

FIG. 4 is an elevation view thereof; and

FIG. 5 is a rear view thereof.

We claim:

The ornamental design for a seat, substantially as shown and described.
